UNITED STATES PATENT OFFICE

PETER J. KING, OF DETROIT, MICHIGAN

ORNAMENTAL STAND

Application filed July 13, 1931. Serial No. 550,613.

This invention relates to improvements in ornamental stands, and refers more particularly to stands employed for such purposes as supporting lamps, spherical maps and other articles.

At the present time it is customary when making ornamental stands for the ornamentation to form an integral part of the stand itself, with the result that in many cases it has not been commercially possible to provide a very wide range of designs from which selection may be made by prospective purchasers on account of the very heavy outlay necessary for patterns. It is an object of this invention to cheapen the production of such ornamental stands by providing one base pattern from which any number of bases may be made, and to provide a plurality of grilles or panels each having different ornamentation thereon, any one of which may be quickly inserted into or removed from the base, thus affording a far greater selection of designs than would otherwise be commercially feasible.

Another object of the invention is to provide an ornamental stand consisting of a base terminating at one extremity in an upwardly and rearwardly inclined portion extending over the base itself, and to provide grilles or panels horizontally slidable between guides provided on the base itself and on the underside of the upwardly and rearwardly inclined portion.

A further object of the invention is to provide such an ornamental stand having a base wherein the sides are spaced from one another for the greater portion of their length, to provide a longitudinal guide between the spaced sides and a second and downwardly projecting guide on the rearwardly inclined portion, so that the underside of a grille or panel may be slidably housed in the first named guide, and upper extremities of ornamentation on the grille or panel slidable adjacent opposite sides of the downwardly projecting guide.

Having thus briefly and broadly enumerated some of the major objects and advantages of the invention, I will now proceed to describe an embodiment of my invention with

the aid of the accompanying drawings, in which:

Figure 1 is a perspective view of the invention.

Figure 2 is an end view thereof, and

Figures 3 and 4 are sections on the lines 3—3 of Fig. 2 and 4—4 of Figure 1.

The stand in the present instance consists of a base formed of two relatively narrow side members 2 and 3 which are connected to one another at one extremity from which they are outwardly flexed from each other to provide a sufficient width of base to eliminate any likelihood of the stand tipping sideways. The ends 2a and 3a of the members 2 and 3 are upwardly and rearwardly flexed and unite to form a common supporting rest 4 which in the present instance is inclined. This rest preferably extends longitudinally and substantially centrally over the base for the greater portion of the length of the latter.

On the underside of the rest 4 a longitudinal guide 5 is provided, and beneath the latter is a lower guide 7. The latter is equipped with upwardly projecting longitudinal margins 7a, and is connected to the base by means of arms 8 which terminate at the inner sides of the members 2 and 3.

The side members 2 and 3, the rest 4, upper and lower guides 5 and 7 and the arms 8 are all integral with one another and constitute the base. The side members 2 and 3 and the rest 4 may be shaped and ornamented in any desired manner, but for reasons which hereinafter become apparent it is desirable that the plane of the central portion of the guide 7 be above the top of the joined extremities of the side members 2 and 3.

10 denotes a grille or panel having its underside longitudinally slidable in the guide 90 7. This grille is suitably ornamented as shown at 12, the upper extremities 12a of portions of the said ornamentation rest against opposite sides of the top guide 5 by which the grille is maintained in an upright 95 position.

As the upper guide 5 is narrower than the underside of the rest 4, and the latter is inclined, when the grille or panel 10 has reached its intended position the upper extremities 100

12a of the ornamentation engage the under-side of the said rest 4 and hold the grille against further movement along its lower guide 7.

5 On the rest 4 is a suitable boss or supporting member 9 is formed upwardly from which an element 9a extends by which any desired article (not shown) may be suitably supported.

10 From the foregoing it will be readily seen that by providing a base as hereinbefore described between guides in which grilles or panels may be selectively mounted, that the cost of making such ornamental stands is materially reduced.

15 When desired screws 6, shown in Figures 2 and 3, may be employed for holding the grille or panel 10 stationary in the lower guide 7; and the advantage of having the central portion of the latter below 20 the jointed extremities of the side members 2 and 3 is to facilitate the insertion and removal of the grilles.

While in the foregoing the preferred embodiment of the invention has been described 25 and shown, it is understood that the construction is susceptible to such modifications and alterations as fall within the scope of the appended claims.

30 What I claim as my invention and desire to secure by Letters Patent is:

1. An ornamental stand comprising a base, a rest extending longitudinally over said base and connected to one extremity of the latter, a guide beneath said rest in substantially the 35 same horizontal plane as said base, and an ornamental grille or panel slidable in said guide, upper extremities of said ornamental grille or panel engaging opposite sides of said rest, and means on the latter for supporting an 40 article to be held thereby.

2. An ornamental stand comprising a base, a rest extending longitudinally over said base and connected to one extremity of the latter, said rest being upwardly and outwardly inclined, a guide beneath said rest in substantially the same horizontal plane as said base, an ornamental grille or panel slidable in said guide, upper extremities of said ornamental grille or panel engaging opposite sides of 45 said rest, projecting portions on said rest for engaging the upper margins of said ornamental grille extremities when the grille has been moved into position on its guide, and means on said rest for supporting an article 50 to be held by it.

3. An ornamental stand consisting of two side members spaced from one another for at least the greater portion of their length to form a steady supporting base, said side members at one extremity being upwardly and backwardly flexed and terminating in a rest extending longitudinally and substantially centrally over said supporting base, a guide integral with said side members and in substantially the same horizontal plane

beneath said rest, an ornamental grille or panel slidable on said guide, upper extremities of said grille or panel engaging opposite sides of said rest to hold said grille in a vertical position, and means on said rest for supporting an article to be held thereby.

4. An ornamental stand consisting of two side members joined to one another at one extremity and spaced from each other throughout the greater portion of their length sufficiently for said members to form a steady supporting base, the other extremities of said side members being upwardly and rearwardly flexed, a rest extending longitudinally and substantially centrally over said supporting base in which said upwardly and rearwardly flexed side member extremities terminate, said rest being upwardly and outwardly inclined, a guide integral with said side members on substantially the said horizontal plane as the latter and beneath said rest, said guide being spaced intermediately between said members, an ornamental grille or panel slidable on said guide, another guide formed on the underside of said rest, upper extremities of said ornamental grille or panel engaging opposite sides of said other guide to hold said grille or panel in place, the upper faces of said extremities engaging portions of said rest which project laterally beyond said other guide when the grille or panel has been slid into position, and means on said rest for supporting an article to be held thereby.
